Application March 28, 1932, Serial No. 601,568

21 Claims. (Cl. 107—54)

This invention relates to mechanism for, and method of, cooling bakery products.

One of the objects of the invention is the provision of new and improved means for controlling the flow of air through a cooling tunnel or passage.

Another object of the invention is the provision of new and improved means for conditioning the air and for controlling its flow across the hot bakery products during the cooling operation.

A still further object of the invention is the provision of new and improved mechanism for cooling bakery products that is inexpensive to install, efficient in use, and which has means for controlling the volume of air flowing through the cooling passage.

Other and further objects and advantages of the invention will appear from the following description taken from the accompanying drawings, in which—

Fig. 1 is a plan view of a bread cooling tunnel or passage with the invention shown in position thereon;

Fig. 2 is a section on the line 2—2 of Fig. 1;
Fig. 3 is a plan view of a modified form of construction;

Fig. 4 is a vertical section on the line 4—4 of Fig. 3;

Fig. 5 is a section on the line 5—5 of Figs. 3 and 4, respectively.

In the cooling of bread, or other bakery products, in long tunnels or long passages with artificial currents of air, moving in a direction contra to the direction of movement of said products or in a direction transversely thereto, it has been found that in order to prevent checking of the crusts and to reduce the loss of weight to a minimum, it is desirable that the air be properly conditioned and that the velocity thereof be reduced toward the end of the passage where the bread is introduced.

Any suitable mechanism may be employed for reducing the velocity of the air entering the outer end of the tunnel as it approaches the inner end or the end adjacent to the oven.

In the form of construction selected to illustrate one embodiment of the invention, the reference character 10 designates generally the cooling tunnel or passage, which may be of the usual or any well-known construction comprising the side members 11, floor or bottom member 12, top member 13 and the end members 14 and 15. The end members 14 and 15 are each provided with a pair of swinging doors 16 and 17, as shown in dotted lines in Fig. 1. Suitable means are provided

for conducting the bakery products through the cooling passage 10.

In the form of construction shown, which is by way of example only, a pair of overhead tracks 18 and 19 extend through the tunnel and are adapted to support a plurality of carriers 21, each of which is supported by suitable rollers 22 and 23 from said tracks. These carriers are of the usual or any well-known construction and each is provided with racks for holding the bakery products. Since the details of these carriers constitute no part of the present invention, it is not thought necessary to describe or further illustrate the same.

Suitable means are provided for circulating conditioned air through the cooling tunnel in a direction contra to the movement of the bread through the tunnel.

As shown in Fig. 2, the carriers 21 move to the right in said figure, and the air is caused to flow in the opposite direction by the mechanism, which will now be described.

The mechanism for circulating the air through the cooling tunnel comprises a blower or fan 25 having an intake passage 26 which is enlarged, as at 27, for containing the air conditioning mechanism, shown in dotted lines in Fig. 2. This mechanism comprises a filter member 29, an air cooling or heating device 28, and a humidifier 31, all of which may be of the usual commercial types and are adapted to maintain the air at a constant temperature and moisture content. If desired, the air may be led through an air sterilizing element 32 of the usual or any well-known construction. The air is admitted to the enlarged portion 27 of the intake through the conduit 33 extending to the exterior of the building in which the cooling tunnel is located. The air passes through the discharge conduit 34 from the fan into the outer end of the tunnel 12 through the nozzle 30, which is substantially the width of the tunnel, as clearly shown in Fig. 1. Suitable mechanism is provided for checking the velocity of the flow of air, as it reaches the inner end of the cooling tunnel. Any suitable mechanism may be employed for this purpose. In the form of construction shown, means are provided at a plurality of points along the cooling tunnel or chamber through which the air may escape, thereby reducing the velocity of the air that remains within the tunnel.

As shown, a conduit 35 is provided above the tunnel and extends longitudinally thereof. The inner end of the conduit 35 is extended to substantially the full width of the tunnel, as at 36,

- and extends into the inner end of the tunnel, as at 37. The outer end of the conduit 35 terminates within the tunnel, as at 38, at a point inwardly of the outer end thereof. The intermediate portion of the conduit 35 has a branch conduit 39 extending downwardly within the tunnel to a point 41 adjacent to the floor of the tunnel. The branch conduit 39 is located between the ends of the conduit 35 and both conduits 38 and 39 are in the vertical plane passing through the center line of the cooling tunnel or chamber. The conduit 35 is provided with an upwardly extending pipe or conduit 42 for taking the air from the conduit 35 to the atmosphere.
- 15 In the operation of the device thus far described, air entering the conduit 38 will pass through the air conditioning mechanism into the blower 25 which will discharge the same into the outer end of the cooling tunnel and cause the same to flow toward the left in Fig. 2. As the air flows along the tunnel toward the inner end thereof, portions of it will flow into the conduit 38, thereby checking the velocity of the flow of air between the conduit 38 and the branch conduit 39. Still more air will be conducted from the tunnel by the branch conduit 39, thereby still further checking the velocity of the air that flows along the tunnel between the branch 39 and the end 37 of the conduit 35.
- 20 It will thus be seen that by the time the air has reached the inner end of the tunnel, a sufficient amount of the same has been withdrawn to materially reduce the velocity of that portion which remains within the tunnel.
- 25 In this form of construction, the heated bread, or other bakery products, when they first enter the cooling tunnel will come in contact with the air that has been heated by the bakery products in the preceding carriers and will be partially cooled by the air in this zone which moves at a very low velocity. Since the velocity of the air is low in the zone where the products enter the tunnel, and the difference in temperature between the air and bread at this point is not so very great, there is little or no tendency of the crust of the bread to check or crack. Furthermore, since the air is conditioned, there will not be much loss in weight due to the evaporation of the moisture from the bread. As the bread, now 30 partially cooled moves further along the tunnel, it will move into the next cooling zone and come in contact with cooler air moving at a slightly greater velocity, which will still further cool the bread. Since the crust was more or less cooled 35 in the first zone, there is not so much danger of its cracking, and, consequently, the air may be caused to flow at a greater velocity in this second zone. In other words, the cooling operation may be hastened in the second zone.
- 40 From the second zone, the bread passes into the third zone where the maximum velocity of the air is encountered and where the cooling operation is considerably hastened over either of the other zones. If desired, the manually controlled dampers or valves 43, 44 and 45 may be provided for controlling the flow of air through either of the outlets at 37, 41 and 38.
- 45 Under certain conditions, it may be desirable to recirculate the air through the cooling tunnel. Bread and other baked products cooled by recirculated air are of higher quality, inasmuch as when the same are cooled in their own aroma, the loss of aroma during the cooling operation is reduced to a minimum.
- 50 In the cooling operation, in order to secure a

uniformity of product, it is necessary that the air be introduced at a uniform temperature and contain a uniform amount of moisture. Suitable means are provided for automatically controlling the recirculation of all or a portion of the air with a view to maintaining a uniform temperature and moisture content of the same as it enters the cooling chamber.

55 In the form of construction shown, an auxiliary conduit 46 is provided for conducting air from the conduit 35 to the enlargement 27 of the intake 26, as shown more particularly in Fig. 1. This conduit 46 is provided with louvres 47 for opening and closing the conduit. The intake pipe 33 is likewise provided with louvres 48 for controlling the flow of air through the same.

60 The louvres 47 and 48 are adapted to be automatically controlled by a thermostat 49 secured in the path of the air discharged from the blower 25, as shown at the right in Fig. 2. This thermostat may be of any usual or well-known construction, that shown being by way of example only. The form shown comprises an expansible member which is adapted to contain an expansible fluid. The louvres 47 are operated from the thermostat 49 by a link 51, a bell crank 52 and a link 53. The louvres 48 are in turn operated from the link 53 through a bell crank 54 and a link 55.

65 When the air discharged from the blower 25 is above a predetermined temperature, the thermostat 49 expands, thereby closing the louvres 47 and simultaneously opening the louvres 48, thus admitting cool air through the pipe 33. When the air discharged onto the thermostat 49 is below a predetermined temperature, the louvres 47 are opened and the louvres 48 closed, and air is drawn from the tunnel through the conduit 35 and the auxiliary conduit 46.

70 If desired, a blower or exhaust fan 77 operated by an electric motor 78 is employed. The speed of the motor is adapted to be controlled by a rheostat 79, the movable arm 81 of which is adapted to be controlled by the movement of the link 55. The parts are so arranged that the speed of the motor will be at its maximum when the louvres 48 are in completely open position, as shown in Fig. 2.

75 By extending the conduit 39 downwardly to a point adjacent to the floor of the tunnel, air will be taken from the lower portion of the tunnel through this conduit. By means of this arrangement, the air will be caused to flow along the lower portion of the tunnel substantially uniformly with that at the top thereof. In other words, the exhaust 41 located at the floor of the tunnel will compensate to a certain extent for the exhaust 38 which is located at the top of the tunnel.

80 While only two intermediate exhausts are shown, it is understood that this number is by way of example only, and that this number may be multiplied. They may also be differently constructed and arranged. The form and arrangement of the exhaust conduits are immaterial so long as a portion of the moving air is removed at intervals along the tunnel for reducing its velocity.

85 The velocity of the air may be varied in the different zones by adjusting the dampers 43, 44 and/or 45 to vary the amount of air removed in those zones.

90 In Figs. 3 to 5 is shown a modified form of the device. In this form of construction, a cooling tunnel or chamber is employed and this tun-

nel may be considered as roughly divided in a plurality of zones. Suitable mechanism is provided for supplying air to all of the zones at a constant temperature, the air moving at different 5 velocities in the different zones.

In the first zone, or the zone wherein the hot bread enters the tunnel, the air moves at a very low velocity and increases successively in the following zones.

10 In the form of construction selected to illustrate one embodiment of this modified form of construction, the reference character 56 designates the cooling tunnel, passage or chamber, which may be substantially of the same dimensions as that disclosed in Fig. 1.

The tunnel or cooling chamber 56 is provided with a pair of overhead tracks 57 and 58 as in the previous construction. Each of these tracks is adapted to support a plurality of carriers 59, 20 each of which is provided with a plurality of racks 61, as is usual in such constructions. In this form of the device, a suitable blower 62 is employed for supplying air to the cooling tunnel. Mounted in the intake 63 of this blower is the 25 air conditioning device 64 which comprises an air filter 290, an air heating or cooling device 280, a humidifier 310, and, if desired, a sterilizer 320, as in the previous construction.

The intake 63 has an upwardly extending pipe, 30 as at 65, which may extend to the exterior of the building for supplying air as needed for the cooling mechanism. The discharge conduit 66 of the blower 62 is extended into the central portion of the tunnel and is in communication with a conduit 67 extending longitudinally of the tunnel and located on the floor along the center thereof. The conduit 67 extends substantially the entire length of the tunnel and is of enlarged cross section at its outer end, the inner end of the tunnel being 35 considerably restricted, as shown at 68 in Fig. 5. The conduit 67 is provided with a plurality of openings or ports 69, 71, 72, 73 and 74 on each side throughout the length thereof.

These ports are provided with suitable valves 45 or gates 75, 76, 770, 780 and 790 which are adapted to be held in adjusted position by any proper means. As shown, these valves are slideable and are adapted to be held in adjusted position by friction of the parts. Extending along the top of 50 the tunnel at each side thereof are the exhaust conduits 810 and 82 (see Figs. 3 and 4). These conduits are preferably located directly above the tracks 57 and 58, respectively.

An exhaust conduit 83 is provided above the 55 central portion of the tunnel. This conduit is bifurcated at its lower end and its furcations 84 and 85 are in communication with the central portions of the conduits 810 and 82, respectively, as shown more particularly in Fig. 4.

60 The furcations 84 and 85 straddle the conduit 66, see Fig. 4. Each of the conduits 810 and 82 is provided with a plurality of intake extensions 86, 87, 88 and 89 which extend through the roof or top 91 of the tunnel 56. These intake extensions are each provided with a valve or damper 92 which is adapted to be independently adjusted for controlling the amount of air exhausted through said extensions. These branches or intake extensions are adapted to exhaust the air 65 from the corresponding zones in the tunnel and may be said, roughly, to divide the said tunnel into different zones.

In the operation of the device, air is drawn 70 through the pipe 65 and discharged through the conduit 66 into the distributor conduit 67, thence

passing up through the ports 69, 71, 72, 73 and 74, respectively, and is exhausted through the branches 86, 87, 88 and 89. The ports 69 are comparatively small and the damper 92 in the branch 86 may be so adjusted that there will be 5 but a small amount of air admitted and exhausted from the first zone at the inner end of the tunnel. In other words, the air in the first zone will be moving very slowly through the first zone. In the other zones, the air will be moving more rapidly 10 until in the last zone, the port 74 will be very large and the damper in the branch 89 may be completely open so that the air will be passed at a maximum velocity across this section of the tunnel. 15

If desired, an exhaust fan 93 operated by an electric motor 94 may be employed for assisting in the exhaust of air through said conduits.

Suitable means may be provided for causing part or all of the air passing through the tunnel 20 to be recirculated. Any suitable mechanism may be employed for accomplishing this function. For the purpose of illustration, the following mechanism may be employed.

A branch or shunt conduit 95 is connected to 25 the exhaust conduit 83 and the intake conduit 65 whereby air may flow from the conduit 83 into the conduit 65. Within the conduit 65 anterior to the branch or shunt conduit 95 are a plurality of louvres 96 and within the conduit 95 are a plurality of louvres 97. Thermostatic means 98 are employed for controlling the operation of the louvres 96 and 97. In the form of construction shown, the thermostat 98 is of the expansible type and the louvres 97 are adapted to be closed 30 by a link 99 which is operated by the thermostat 98. The louvres 96 are simultaneously opened by a bell crank 100 and link 101 which are operated by the extension of the link 99. Suitable means are provided for controlling the speed of the 35 motor 94. As shown, a rheostat 102 may be employed for this purpose. The rheostat may be controlled by an extension of the link 101 which operates the contact member 103.

The thermostat 98 may be located in any convenient part of the cooling tunnel. For the purpose of illustration, it is shown as being located in the last zone, or outer end of the tunnel, and

when the air surrounding the thermostat rises above a predetermined temperature, the thermostat will expand as shown in Fig. 5, thus closing the louvres 97 for preventing recirculation of the air through the shunt 95 and simultaneously opening the louvres 96 for permitting air to enter through the intake 65. The movement of the link 101 for opening the louvres 96 will move the contact arm 103 of the rheostat 102 into electrical communication for causing the motor to operate at its maximum speed. When the air falls below a predetermined temperature, the reverse operation takes place. 50

The specific details of the air conditioning device, the controls and the like are not disclosed 55 since commercial forms of these devices are employed. In the air conditioning device, for instance, the heater or cooler may be coils of pipe for circulating hot or cold water through the same for heating or cooling the air, as occasion may require, or sprays of hot or cold water may 60 be employed for washing and for heating or cooling the air as required. Usually the air entering the intake of the blowers will be cooled but under certain conditions it may be desirable to heat 65 the same. 70

Furthermore, where a spray of water is employed for heating or cooling the air, a separate humidifier may not be necessary. The sterilizer may be of any suitable commercial type, such as 5 an ozonizer or a device for utilizing the violet ray. The controls are likewise shown more or less diagrammatically and may be of the usual or any well-known construction. By means of this 10 conditioning device, the air entering the blower is maintained at a uniform temperature and moisture content, whereby the bread is not only cooled but its weight and moisture content is maintained constant.

It is thought from the foregoing taken in connection 15 with the accompanying drawings that the construction and operation of my device will be apparent to those skilled in the art and that changes in size, shape, proportion and details of construction may be made without departing 20 from the spirit and scope of the appended claims.

What I claim, therefore, is:

1. A method of cooling bakery products which comprises moving the same along a cooling tunnel 25 and simultaneously causing a stream of air to flow in the tunnel contra to the direction of the movement of the bakery products and with decreasing velocity as it flows through said tunnel.

2. In an apparatus for cooling bakery products, 30 a cooling passage, means for conveying said products through said passage in one direction, means for conditioning air as to temperature and moisture and for causing the same to flow through said passage in a direction contra to the movement 35 of said products therethrough and means including exhaust ports for reducing the volume of air during its travel through said passage.

3. In a cooling apparatus for bread and other products, a cooling tunnel, means for conducting 40 said products through said tunnel, means for causing a stream of air to flow through said tunnel in a direction contra to the direction of movement of said products, and means at a plurality of zones along said tunnel for progressively 45 reducing the volume of said stream of air as it passes through said zones.

4. In a cooling device for bakery products, a cooling tunnel, means for conducting bakery products through said tunnel for cooling the 50 same, means for causing a stream of air to flow through said tunnel in a direction contra to the movement of said products therethrough and means at a plurality of points along said tunnel for removing a portion of said air as it passes 55 said points.

5. A method of cooling bakery products which consists in placing the products in a cooling tunnel, subjecting said products while at their highest temperature to a current of air at low velocity and immediately afterward treating the same 60 with currents of air at progressively higher velocities.

6. A method of cooling bread which consists in subjecting the same immediately after it comes 65 from the oven and while in its highly heated condition to a current of air conditioned as to temperature and moisture and at low velocity for initially cooling the bread without checking or cracking the crust and immediately there- 70 after subjecting the partially cooled bread to a current of air conditioned as to temperature and moisture at a higher velocity for further cooling said bread.

7. A method of cooling bakery products which 75 consists in causing a current of air at a prede-

termined temperature and moisture content to flow across said products at low velocity while the products are at their highest temperature after removal from the oven, then causing air at the same temperature and moisture content 5 as the first named air to flow across said products at a higher velocity for finishing the cooling operation.

8. A method of cooling bread and other bakery products which consists in moving the products 10 along a tunnel and simultaneously subjecting the same to a flow of sterilized air of decreasing velocity toward the outer end of the tunnel.

9. A method of cooling bread which consists in conducting bakery products along a conduit, 15 conducting along said conduit a counter flow of air at a velocity that decreases at a plurality of zones as it flows along said conduit and at a predetermined temperature and having a predetermined moisture content. 20

10. In cooling apparatus for bakery products, a cooling tunnel, means for conducting bakery products through said tunnel for cooling the same, means for causing a current of air of low velocity to flow across a section of said tunnel 25 adjacent the entrance end thereof, and means for causing a stream of air of higher velocity to flow across a section of the tunnel adjacent the delivery end thereof.

11. In cooling apparatus for bakery products, 30 a cooling tunnel, means for conducting bakery products through said tunnel for cooling the same, means for causing a current of air of low velocity to flow across a section of said tunnel adjacent the entrance end thereof, and means for 35 causing a stream of air of higher velocity to flow across a section of the tunnel adjacent the delivery end thereof, and means for conditioning said second stream of air as to temperature and moisture. 40

12. A method of cooling bakery products which comprises passing said products through a cooling tunnel and simultaneously supplying air conditioned as to temperature and moisture to said tunnel and causing the air to move at different 45 velocities in different portions of said tunnel, the velocity of the air in the end portion of the tunnel where the products enter the same being the lowest.

13. In an apparatus for cooling bakery products, a cooling passage adapted to receive bakery products at its inner end and discharge the same at its outer end, means for introducing air conditioned as to temperature and moisture into the outer end of said passage, and means for materially reducing the volume of the air flowing 55 through the inner end of said passage. 50

14. In an apparatus for cooling bakery products, a cooling passage, means for conveying bread through said passage from the inner to 60 the outer end thereof, means for conditioning air as to temperature and moisture and causing the same to flow through said passage contra to the direction of movement of said products, and means for reducing the volume of the air flowing 65 into the inner end of said passage.

15. In a cooling apparatus for bakery products, a cooling tunnel, means for conducting bakery products through said tunnel from the inner to the outer end thereof, means for conditioning air as to temperature and moisture and for supplying said air to said tunnel for cooling said products, and means for causing said air to flow at various speeds in said tunnel, the volume of said air being at a minimum in the inner end 70 75

portion of said tunnel and at a maximum in the outer end thereof.

16. A method of cooling bread which consists in moving the bread through streams of cooling air of different velocities, the stream to which the bread is initially subjected moving at a lower velocity than that to which the bread is finally subjected.

17. In a cooling apparatus for bakery products, 10 a cooling tunnel of substantially uniform cross section, means for conducting bakery products from the entrance to the delivery end of said tunnel for cooling the products, means for causing a current of air of predetermined volume to 15 flow in a section of said tunnel adjacent the entrance end thereof, means for causing a stream of air of greater volume to flow in a section of the tunnel adjacent the delivery end thereof, and means for recirculating a portion or all of said 20 air through said tunnel.

18. A method of cooling bakery products which comprises causing air to flow over said products at comparatively low velocity while the products are at high temperature from the baking operation, 25 and then causing air at higher velocity to flow over said products for continuing the cooling operation.

19. In an apparatus for cooling bakery products comprising a cooling passage, means for 30 conducting bakery products through said passage, an air conduit having a plurality of ports adjacent to the floor of said passage spaced lengthwise of said passage through which conditioned air may be discharged into said passage 35 at intervals throughout the length thereof, ad-

justable valve members for said ports, means within said conduit for conditioning air passing therethrough as to temperature and moisture, a blower in said conduit for causing the air to flow therethrough, an air discharge conduit having a plurality of ports opening into said passage at intervals lengthwise thereof, valves in said ports for controlling the amount of air discharged therethrough, a shunt passage for connecting said conduits, and thermally controlled means 10 for causing a portion or all of the air passing into said discharge conduit to be recirculated through said passage.

20. In a cooling apparatus for bakery products, a cooling tunnel, means for conducting 15 bakery products through said tunnel from the inner to the outer end thereof, means for conditioning air as to temperature and moisture and for supplying said air to said tunnel for cooling said products, means for causing said air to flow 20 at various speeds in said tunnel, the volume of said air being at a minimum in the inner end portion of said tunnel and at a maximum in the outer end thereof, and means for recirculating a portion of said air through said last-named 25 means and within said tunnel.

21. A method of cooling bread which consists in moving the bread through streams of cooling air of different velocities, the stream to which the bread is initially subjected moving at a lower 30 velocity than that to which the bread is finally subjected, and simultaneously causing portions of said air to be recirculated over said bread during the cooling operation.

WADE W. REECE. 35
